(57) **CLAIM**

The ornamental design for a dispenser for rolled sheet material, as shown and described.

DESCRIPTION

FIG. 1 is a front view of a dispenser for rolled sheet material; FIG. 2 is a back view of the dispenser of FIG. 1;

FIG. 3 is a top view of the dispenser of FIG. 1;

FIG. 4 is a bottom view of the dispenser of FIG. 1;

FIG. 5 is a right side view of the dispenser of FIG. 1, the left side view being a mirror image thereof; and,

FIG. 6 is a cross sectional view taken along line 6—6 of FIG. 1.

The broken lines shown in the drawing disclosure are for illustrative purposes only and form no part of the claimed design.
